(57) **CLAIM**

The ornamental design for a patient monitoring sensor, as shown and described.

DESCRIPTION

FIG. 1 is a perspective view of the patient monitoring sensor in a closed position;

FIG. 2 is a perspective view of the patient monitoring sensor in an open position;

FIG. 3 is a front elevational view of the patient monitoring sensor in a closed position;

FIG. 4 is a back elevational view of the patient monitoring sensor in a closed position;

FIG. 5 is a top plan view of the patient monitoring sensor in a closed position;

FIG. 6 is a bottom plan view of the patient monitoring sensor in a closed position; and,

FIG. 7 is a right side elevational view of the patient monitoring sensor in a closed position, the left side elevational view being a mirror image thereof.

Where utilized, phantom lining is for illustrative purposes only and is not intended to limit or form any part of the claimed design.
